UNITED STATES PATENT OFFICE.

FRANK H. TURNER, OF HARTFORD, CONNECTICUT, ASSIGNOR TO THE
HARTFORD RUBBER WORKS COMPANY, OF SAME PLACE.

DESIGN FOR A RUBBER FOOT-MAT.

SPECIFICATION forming part of Design No. 33,571, dated November 13, 1900.

Application filed October 16, 1900. Serial No. 33,299. Term of patent 7 years.

to all whom it may concern:

Be it known that I, FRANK H. TURNER, a citizen of the United States of America, residing at Hartford, in the county of Hartford and State of Connecticut, have invented a new and original Design for Rubber Foot-Mats, of which the following is a specification, reference being had to the accompanying drawings, forming a part thereof, wherein—
5 o Figure 1 is a plan view of a foot-mat embodying such a design. Fig. 2 is a view thereof in cross-section on the plane denoted by the dotted line *x x*.
One feature of the design consists in the 5 rectangular corrugations *a*.

Another feature of the design consists in the corrugations of diamond form *b*.

Still another feature of the design consists in the slight corrugations *c*, which are inside of the diamonds.

Having described my design, what I claim as new, and desire to secure by Letters Patent, is—

The design for a rubber foot-mat as herein shown and described.

FRANK H. TURNER.
